UNITED STATES PATENT OFFICE.

ROBERT L. SMYTHE, OF MILWAUKEE, WISCONSIN, ASSIGNOR TO LINE MATERIAL COMPANY, OF SOUTH MILWAUKEE, WISCONSIN, A CORPORATION OF WISCONSIN.

ELECTRICAL SWITCH.

Application filed August 19, 1927. Serial No. 214,121.

This invention relates to improvements in electrical switches and refers more particularly to a disconnecting switch adapted to be incorporated within a high voltage transmission line to facilitate the disruption of a section of the line for the purpose of repairing or replacement. The switch is generally mounted upon a tower, pole or other support, and is usually controlled with two similar units by a single device located at a remote point.

Switches of this character are designed to carry high voltage current thereby necessitating the provision of a quick make and break to eliminate destructive arcing forces. It is also highly desirable that the gap between the switch parts be as wide as possible to prevent jumping of current thereacross.

It is therefore an object of this invention to provide a switch of the character described in which the movable member moves at a relatively high speed to eliminate, as much as possible, destructive arcing forces.

Another object of this invention resides in the provision of a switch of the character described, having a movable member so constructed that the initial opening force applied to the element is relatively great and the movement thereof from a predetermined point is accelerated.

A further object of this invention resides in the provision of a switch of the character described in which the movable member is composed of two pivoted sections so arranged that the opening force is applied to move both sections in unison to a predetermined point, continued movement of the opening means causing one of the sections to rapidly pivot about its connection with the other section.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far de-

vised for the practical application of the 55 principles thereof, and in which:

Figure 1 is a side elevational view of my improved switch construction with parts broken away to illustrate details of construction;

Figure 2 is an end view of the switch taken on the plane of the line 2—2 of Figure 1; and,

Figure 3 is a fragmentary view illustrating the various positions of the movable 65 member.

Referring now more particularly to the accompanying drawings, in which like numerals designate like parts throughout the several views, the numeral 5 designates a 70 mounting base of channel iron or the like, which may be a part of the tower or other support for the switch unit and on which two pedestals 6 are mounted by being bolted or being otherwise secured, as at 7. The base 75 or supports 8 of suitable insulators 9 and 10, preferably of the petticoat type, are bolted or otherwise secured to the pedestals, as at 11'. As clearly illustrated, the insulators are spaced apart and when the switch unit 80 is mounted vertically they are preferably inclined to direct the top face of the insulators upwardly.

Suitably fixed to the outer end of the insulator 9 is a bracket member 11 on which 85 is mounted the stationary contact 12 of the switch. This contact may be of any suitable construction, and in the present embodiment includes a pair of switch clips 13, one of which is spring urged to engagement with 90 the other and between which the end portion 14 of the movable switch member 15 is engageable. The adjacent transmission line 16 is electrically connected with the contact 12 by a terminal 17 and is anchored to the 95 bracket member 11 by a clamp 18.

The other insulator 10 has a bracket member 19 suitably secured to its outer end substantially in line with the bracket member 11, and the movable switch member 15 100 which consists of a lower section 20 and an upper section 21, pivotally connected thereto as at 22, is pivoted to the bracket member at 23.

As best illustrated in Figure 2, the sections of the movable switch member are formed of two spaced members, the lower section 20 consisting of angle irons 24 held

in substantially parallel spaced relation at their upper ends by a transverse member 25 and at their lower ends by that portion of the bracket member 19 to which the section is pivoted, diagonal braces 26 giving added rigidity to the structure. The upper section 21 is formed of two substantially flat side members 27 spaced apart at their lower ends a distance to fit within the space 10 between the angle iron sides of the lower section and being held in the proper relation by a transverse member 28 having its ends directed laterally to engage the outer faces of the side members 27. That portion of 15 the side members 27 upwardly of the transverse member 28 are converged and receive therebetween at their outer end the contact member 14 which is of the knife blade type. The connection between the blade contact 20 and side members is, what might be termed, "sloppy" allowing a limited pivotal movement of the blade with respect to the sides to more readily break any mechanical freezing of the switch blade with the contact 25 12.

The lower end of each side member 27 of the upper section has a cam plate 29, to be later described, connected therewith and extended inwardly of its end, the plate being 30 secured to the side member 27 by rivets or other means 30, which also pass through the lateral portions of the transverse member 28. The pivot 22 connecting the two sections of the movable switch member passes 35 through the cam plates as well as the side members 27 and the angle iron members 24.

Opening and closing movements are imparted to the movable switch member by an actuating lever 31, fixed to a shaft 32, suitably journaled in bearings 33 mounted on the base 5, and which may be extended to 40 actuate any number of switch units, being rotated from an operating lever, not shown, connected with a rod 34 pivoted to a lever 45 connected with the shaft. A mounting member 36 is pivoted to the outer end of lever 31 and has the base 37 of an insulator 38 secured thereto, the other end of the insulator 38 having a head 39 mounted thereon. A left and right threaded stud 40 adjustably connects the head 39 with a link 41 pivotally connected with the movable switch member at 42, the pivot 42 passing through the laterally extended portions of 50 the transverse members 28.

The two sections of the movable switch member move in unison and in longitudinal alignment throughout a predetermined degree of opening movement being locked in 60 this relation by the engagement of a transverse pin 43 with a recess 44 in the cam plate, the pin being carried at the outer end of a link member 45 which is positioned between the sides 24 of the lower section and 65 pivotally mounted from an upwardly ex-

tended portion 46 of the bracket member 19 as at 47. Rollers 48 carried by the pin relieve the same of undue wear, and facilitate the movement of the switch. The pin 43 has its outer ends passed through elongated apertures 49 in the side portions of the member 24, the length and position of which is such that when the switch is in fully closed position, as illustrated in Figure 1, the pin 43 engages the upper outer 75 end thereof.

As the switch member, in its opening movement, approaches a position depicted by the full lines in Figure 3, pin 43 is withdrawn from the cam recess and engages the 80 lower or inner end of the elongated slot 49 arresting the movement of the lower section 20, continued opening movement causing the upper section 21 to pivot about the pivotal connection 22 which becomes stationary. It 85 will be apparent that the movement of the upper section about the pivot 22 is relatively fast thus quickly obtaining the necessary distance between it and the stationary contact. 90

In closing, the operation is substantially the reverse, the link 45 causes the pin to travel upwardly in the slot and into engagement with the cam recess. The engagement of the pin with the upper end of the slot 95 locates the lower section in its proper position and a stop pin 50 carried by the cam plates abuts the sides of the lower section to positively align the sections and prevent their buckling with respect to each other. 100

The blade 14 is electrically connected with the other end 51 of the transmission line by a flexible conductor 52 clamped to the blade, as at 53, and electrically connected with a terminal 54 with which the end of the transmission line is connected, a clamp 18 anchoring line 51 to the bracket member 19. 105

If desired, a sleet hood 55 may be mounted on the bracket member 11 to protect contact 12 and blade 14. 110

What I claim as my invention is:

1. In combination, a movable switch member including two sections pivotally connected at their adjacent ends, means pivotally mounting the outer end of one section, a contact terminal with which the outer end of the other section is engageable, means for securing the sections in longitudinal alignment when the switch is closed, and means cooperating with said securing means whereby one section remains stationary during opening movement beyond a predetermined degree. 115

2. A movable switch member including two sections having their adjacent ends pivotally connected, means pivotally mounting the outer end of one section, a contact terminal with which the outer end of the other section is engageable, means for swinging the switch member to open the switch, and 125 130

means whereby the sections remain in longitudinal alignment through a predetermined period of opening movement and whereby further opening movement causes the sections to assume an angular position with respect to each other.

3. A movable switch member, including two sections having their adjacent ends pivotally connected, a support pivotally mounting the outer end of one section, a contact terminal with which the outer end of the other section is engageable, means for swinging the movable switch member to open the switch, cooperating means carried by the second-mentioned section and pivoted to the support to which the first-mentioned section is pivoted whereby the sections move in longitudinal alignment throughout a predetermined period of opening movement and during continued opening movement the first-mentioned section is arrested.

4. A movable switch member including two sections having their adjacent ends pivotally connected, a support to which the outer end of one section is pivoted, a contact terminal with which the outer end of the other section is engaged, means for swinging the switch member to open the switch, a cam member carried by the second-mentioned section, and a link pivoted to the support and having its outer end engageable with the cam, whereby the sections travel in longitudinal alignment throughout a predetermined degree of opening movement and during continued movement the first section is arrested.

5. A movable switch member including two sections having their adjacent ends pivotally connected, a support to which the outer end of one section is pivoted, a contact terminal with which the outer end of the other section is engaged, means for swinging the switch member to open the switch, a cam member carried by the second-mentioned section, and a link pivoted to the support and having its outer end engageable with the cam whereby the sections travel in longitudinal alignment throughout a predetermined degree of opening movement and during continued movement of the first section to open positions the same is arrested, causing the second mentioned section to pivot about its connection with the first mentioned section.

6. A movable switch member including two sections having their adjacent ends pivotally connected, means pivotally mounting the outer end of one section, a contact terminal with which the outer end of the other section is engageable, means for swinging the switch member to open the switch, means for securing the sections in longitudinal alignment, and means for rendering said last mentioned means inactive after the switch member has been opened a predetermined degree to permit the sections to assume an angular position with respect to each other upon further opening of the switch.

In testimony whereof I have hereunto affixed my signature.

ROBERT L. SMYTHE.
